UNITED STATES PATENT OFFICE.

GUY B. BROWN, OF GARDNER, MASSACHUSETTS.

MACHINE FOR SHAPING ARTICLES.

1,407,724.

Specification of Letters Patent. Patented Feb. 28, 1922.

Application filed February 15, 1921. Serial No. 445,056.

To all whom it may concern:

Be it known that I, GUY B. BROWN, a citizen of the United States, residing at Gardner, in the county of Worcester and 5 State of Massachusetts, have invented new and useful Improvements in Machines for Shaping Articles, of which the following is a specification.

My invention relates to machines for 10 forming articles of various sorts from wood, and particularly to machines for forming chair bottoms from wooden blanks.

The object of my invention is to provide 15 a simple and efficient machine of the character referred to by means of which wooden blanks for chair bottoms, or other articles, may be expeditiously and accurately trimmed to the desired predetermined shape.

The invention is embodied in the improvements hereinafter described and claimed.

Of the accompanying drawings forming a part of this specification,—

Figure 1 is an elevation of a machine embodying my invention, said machine being 25 particularly designed for shaping chair bottoms.

Figure 2 is a plan view, partly broken away, of the machine shown in Figure 1.

Figure 3 is a section on line 3—3 of Figure 2.

Figure 4 is a sectional detail hereinafter described.

Figure 5 is an elevation showing the two templates or cams for controlling the engagement of the cutting devices with the wooden blank.

Figures 6 and 7 are views, more or less diagrammatic, illustrating the operations carried out in shaping a chair bottom, the 40 parts in both figures being viewed toward the axis or center of the machine.

Figure 8 is a detail hereinafter described.

The machine herein shown comprises a bed or table 1, provided with legs 2, resting upon the floor, and having secured to its top side bearing boxes 3, in which is journaled a horizontal shaft 4. The shaft 4 carries a pulley 5, to receive upon it a belt through which the pulleys and shaft are 50 continuously driven. The table 1 is made with a central hub 6, to which is bolted a bearing 7 surrounding a vertical post 8 that is provided with a threaded hole at its lower end to receive within it a screw 9 by means of which the post 8 is supported with

provision for adjustment vertically. The shank of the screw 9 is rotatably mounted in a cross-bar 10 connected with two of the legs 2, and at its lower end is provided with a hand wheel 11 by means of which the screw may be manually rotated. The post 8 is formed with a vertical slot 8^a, through which the shaft 4 extends, so that the post 8 is free to be adjusted vertically relatively to shaft 4, and at the same time 65 the latter holds, or assists in holding, the post against rotating on its vertical axis, the interior of the bearing sleeve 7 and the exterior of that portion of post 8 mounted therein being cylindrical. At its upper end 70 the post 8 is made with a socket 12 within which are secured, by bolt 15, the lower ends of two uprights or brackets 13 and 14, those portions of the uprights 13 and 14 immediately above the post 8 being constructed to 75 jointly provide a trunnion upon which is rotatably mounted a sleeve 16. Said sleeve, (Figures 3 and 8), is formed at its upper end with four sets of gear teeth 17 alternating with smooth or untoothed concave 80 surfaces 20 to be operated by the member 18 having a toothed portion 19 and the rest of its periphery being smooth. These two gears 17 and 18 are of the same pitch diameter and are constructed so that, during 85 one-quarter of the revolution of gear 18, the latter, through the engagement of its teeth 19 with the teeth of the gear 17, rotates the latter one-quarter of a revolution, while during the remaining three-quarters 90 of the revolution of driving gear 18 the engagement of the smooth or untoothed concentric periphery thereof with one of the four smooth concave portions or sockets 20 of gear 17 (Figure 8) serves to lock the latter at rest and against rotative displacement. Thus, for each revolution of gear 95 18 the gear 17 first makes one-quarter of a revolution, during one-quarter of the revolution of gear 18, that is, while the 100 teeth 19 engage one of the sets of teeth 17 and then, during the other three-quarters of a revolution of the gear 18 its smooth concentric portion rides over a concave portion 20.

Extending radially outward from sleeve 16 are four arms 21, integral at their inner ends with a hub 22 surrounding the sleeve 16 and fastened to the latter by bolts 23. It will thus be clear that sleeve 16 and hub 22 110

with its arms 21, make up a turntable or turret that is intermittently operated step-by-step by gears 17 and 18.

At its outer end each arm 21 is made with vertical ways in which is mounted a slide or head 24 in which is journaled a horizontally-disposed spindle 25 whose inner end is connected through a universal joint 26 with an extensible shaft section 27, whose opposite end is connected through a universal joint 28 with a short shaft or clutch member 29 mounted to slide endwise and rotate within a bearing provided in sleeve 16. As will be clear from Figure 3, the inner end of each clutch member 29 is constructed with a clutch face, while near its outer end it is formed with an annular groove that is occupied by a roll 30, (Figure 8), carried by a slide 31. Each slide 31 is mounted upon the top of one of the arms 21 with provision for movement radially.

Each spindle 25 has its outer end portion threaded to receive upon it a nut 32 (Figure 4) by means of which a plate or head 33 is securely fixed to the end of said spindle. This head or plate 33 has secured to it, by means of screws 34, two cams or templates 35 and 36 cooperating, respectively, with rolls 37 and 38, loosely mounted on the shaft 4. The cams or templates 35 and 36 are at different distances from the vertical axis of the sleeve 16 and, therefore, the rollers 37 and 38 are also located at different distances from the vertical axis of the machine. At its upper end, each slide 24 is made with an outwardly and downwardly extending arm 39 provided at its lower end with a threaded hole within which is mounted a screw 40 carrying a hand wheel at its outer end. At its inner end each screw 40 has swivelly connected therewith a head or plate 41, between which and the head or plate 33, the chair bottom blank B is clamped. As will be clear, the blank B is securely clamped between the two plates or heads 41 and 33 by means of the screw 40. The outer face of the plate or head 33 (Figure 4) is made with pointed studs 42 which enter the blank and ensure rotation of the latter with the head or plate 33, the latter being connected with the spindle 25 by means of a key 43.

The driving gear 18 is fast on a shaft 44 journaled in bearings on the two uprights or brackets 13 and 14, said shaft carrying a fast pulley 45 to receive upon it a driving belt (not shown), through which the shaft 44 is continuously driven while the machine is in operation. Alongside of pulley 45 is arranged a loose pulley 46 on to which the belt can be shifted when it is desired to stop the operation of the machine. During each period of rest of the sleeve 16, two of the slides 24 occupy positions immediately above the shaft 4 with the blanks carried by said slides each in position immediately above

a cutter head 47, said cutter heads being rigidly secured to the outer ends of the shaft 4. When the two slides 24 occupy these positions the cam or template 35 of the slide at the right (Figures 1, 2 and 3), rests upon the roller 37 as indicated in Figure 6, while the cam 36 of the slide 24 at the left in said figures, rests upon the roller 38 as shown in Figure 7. While the parts are in these positions the two spindles 25 of the two slides referred to are rotated, and, as will be clear, the cam 35 of the slide 24 to the right will control the engagement of the cutter 47 with the blank B carried by that slide, while the engagement of the cam 36 with the roll 38 at the left will control the engagement of the cutter 47 at that side of the machine with the other blank B.

During the operation of the machine the blanks are placed in position in the machine and removed from the latter by an attendant who stands in front of the machine as viewed in Figure 1. After a blank has been secured in position upon one of the slides 24 the first step movement of sleeve 16 carries that blank into position immediately above the cutter 47 at the right, and while the blank dwells at this position it is rotated through the means presently to be described to the extent of about one revolution and a half, the cutter 47 engaging the blank first along one edge, and then along the opposite edge thereof, as illustrated in Figure 6. The next step movement of sleeve 16 carries the blank away from the cutter 47 at the right, and the third step movement of said sleeve carries the blank into position immediately above the cutter 47 at the left. While in this last position, the blank is again rotated to the extent of about one revolution and a half during which the cutter 47 operates upon the previously uncut edge portions of the blank to complete the shaping thereof, as illustrated in Figure 7. During the time that the blank occupies a position above either cutter, one or the other of the cams 35 or 36 occasions movement of the blank toward and from the cutter, to control the engagement of the cutter with the blank, so that the cutter operates upon the blank only in the direction of the grain of the wood, or across the grain, but at no time against the grain.

The fourth step movement of the turret or turn-table brings the now finished chair seat to the unloading and loading position, and the attendant removes the finished seat and substitutes another blank. The speed at which the gear 18 is driven affords time for this during each period of rest of the turn-table.

The means for rotating the blank while the latter is in position above either cutter 47, includes a train of spur gears 48, 49 and 50, pocketed between the two uprights 13

and 14. The relative sizes of the gears of the train being such as to effect about one revolution and a half of the gear 50 during the time that the untoothed portion of the gear 18 is riding over a concave portion 20 of the member 17. The gear 48 is fast on the shaft 44, and rotates continuously with the latter, while the gear 49 is an intermediate through which the gear 48 drives the gear 50. This gear 50 has both ends of its hub made with clutch faces to cooperate with the inner clutch ends of the members 29. As each pair of slides 24 come into position immediately above the shaft 4 the two members 29 connected with the spindles 25 of said two slides register with the ends of the hub of the gear 50 and are moved inwardly into engagement with said ends so that the two spindles 25 are then driven from the shaft 44 through the gears 48, 49 and 50, members 29, and extensible shaft sections 27. Each extensible shaft section 27 includes a spring 51, and these springs are the means for shifting the clutch members 29 inwardly to engage the hub of gear 50 as described, when brought into register with the ends of said hub.

The shaft 44 carries a cam 52 cooperating with the rolls 53 that are provided on the slides 31. The outer side of gear 18 (Figure 8) is also made with a cam 54 to cooperate with said rolls 53. After two of the slides 24 have been brought into position over the cutters 47 and the blanks have been rotated as described, the two cams 52 and 54 simultaneously engage the rolls 53 of the two slides 31 that are connected with the clutch members 29 of those two slides 24, and through this engagement the cams force the two slides 31 outwardly, shifting the two clutch members 29 out of engagement with the ends of the hub of gear 50. Immediately thereafter the gear 18 imparts a 90° step movement to the sleeve 16. At the start of this 90° step movement and while the rolls 53 are held at their outermost positions by the cams 52 and 54, the inner ends of the slides 31 are carried into position immediately outside of two segmental abutments 55, (Figures 2 and 8) by which said slides are held at their outermost positions during 180° movement of the turntable and until the two clutch members 55 connected with their slides are brought again into register with the hub of gear 50. As will be clear, the rotation of the cams 52 and 54 around the axis of shaft 44 carries said cams upwardly out of engagement with, and out of the path of, the two rolls 53 referred to, immediately after the slides 31 move into position outside of the segmental abutments 55.

While each slide 24 occupies a position over one of the cutters 47 said slide is sup-

ported by one of the rolls 37 or 38, with which the cams 35 and 36 cooperate, and in order to support the slides 24 while they are traveling from one cutter to the other, and while at rest between the cutters, I provide tracks 56 cooperating with rolls 57 provided at the lower ends of the slides. As each slide 24 passes away from position above either one of the cutters 47 its roller 57 rides on to one or the other of the tracks 56, by which the slide 24 is supported until it comes into position over the other cutter 47. As shown in Figures 1 and 3, the tracks or rails 56 are made inclined so as to cam the slides 24 upwardly as they travel from one cutter 47 to the other, thus causing the cams 35 and 36 to approach the rolls 37 and 38 from above as they come into position opposite the cutters. In this way the cams or templates 35 and 36 are prevented from striking against the sides of the rollers 37 and 38 as they are brought into position opposite the latter, which would interfere with the step movements of the sleeve 16.

Each extensible shaft section 27 comprises a tubular member 59, within which is telescopically fitted a male member 60 that is splined to said tubular member, so that the latter when driven by gear 50, transmits rotary motion to member 60 and the spindle 25 that is connected therewith. The spring 51 of each extensible shaft section is arranged within the tubular member under compression, and bears at its ends against the two members 59 and 60 so as to tend to separate the same.

The two cams 35 and 36 of each pair are, as herein shown, counterparts and each is constructed with elevations 61 which, through their engagement with the rolls 37 and 38, serve to hold the blank out of engagement with the cutters 47, while each cutter is moving bodily relatively to the blank against the grain of the latter, as will be clear from Figures 6 and 7, the grain of the wooden blank B in said figures being indicated by the horizontal tinting lines. Also, each cam is made with depressions 62 which not only permit the blank to descend by gravity into engagement with the cutters, but which correspond in shape to the shape that it is desired to give to the edge of the blank. Thus it will be clear that the cams 35 and 36 control the engagement of the cutters with the work, so that said cutters act on the blank only in a direction with the grain of the wood, or across the grain, with the result that the edge of the blank is smoothly finished to the desired shape, and the cutters cannot "run into" or split the blank.

Bearing in mind that Figures 6 and 7 are views looking in opposite directions, it will be understood that the teeth of the two cutters face in the same direction relatively to

the direction of rotation of the shaft 4, so that after the blank leaves the first cutter 47 and is brought into position opposite the other or second cutter 47, it is possible for the latter to complete the trimming or shaping of the blank without operating against the grain of the latter.

For different sizes of articles to be operated upon, the post 8 and the superstructure 10 carried thereby is adjusted by means of the screw 9. For different shapes of articles, interchangeable and properly formed templates or patterns 35, 36, are removably secured to the head 33, as by means of the 15 screws 34.

The operation or method of shaping the blanks will now be described, reference being had particularly to Figures 6 and 7. It is to be understood, however, that said operation or method might be effected by mechanism in an embodiment other than that illustrated in Figures 1, 2 and 3, or might be effected by hand with the aid of a suitable cutter.

25 In Figures 6 and 7 the dotted circles indicate some of the positions of one or the other of the cutters 47 relatively to a blank and the templates, said figures, by means of the arrow lines, indicating the direction of relative movement. Of course, with the machine illustrated, the cutters do not move around the blank as might be understood from Figures 5 and 6, but the blank itself rotates. To attempt to illustrate, in any one figure, 30 rotative positions of the blank would result in the employment of many confusing lines. Hence, for descriptive purposes, the apparent indication that the cutters travel around the blank.

40 Referring now to Figure 6, assume that the cutter begins to operate on the blank B at the point *a*, and the relative movement of the cutter and blank is such that the cutting progresses toward the point *b*, and, therefore, the cutting is along with the grain of the wood. The cutting then progresses across the grain to the point *c*, the depression 62 of the template 35 permitting such cutting. Before the cutting can reach a 45 point near the corner of the blank where splitting of the wood might occur, one of the elevations 61 of the templet separates the blank and cutter and preserves such separation until a point such as *d* is reached. Then 50 the other depression 62 of the template permits resumption of cutting, first with the grain, and then across the grain to the point *e*. It will be now understood that no cutting is effected except in directions with the grain 55 and partly across the grain, but never against the grain, or at points where a corner might be split off. When the blank is then carried around to be acted upon by the other cutter, and under the control of the template 36 (Figure 7) said template first

permits cutting from point *f*, and around the corner to a point where it laps on to the former cut at *e*. Separation then occurs and cutting is resumed at point *g* and proceeds with the grain to point *h*, and then across the grain to a point where it laps the former cut at *e*. The points of starting and resuming the cutting obviously need not be exactly as illustrated in Figures 6 and 7.

I claim:

1. A machine of the character described, comprising an intermittently rotatable turret having a plurality of vertically movable carriers, a spindle having a pair of templates mounted in each carrier, means for securing a blank adjacent to each pair of templates, means for rotating the spindles, templates and blanks, cutters for simultaneously operating on two of the blanks, means coacting with the templates for varying the positions of the blanks relatively to the cutters, and means independent of the templates for raising the carriers and the parts carried thereby as they move from one cutter to the other.

2. A machine of the character described, comprising an intermittently rotatable turret having a plurality of vertically movable carriers, a spindle having a pair of templates mounted in each carrier, means for securing a blank adjacent to each pair of templates, means for rotating the spindles, templates and blanks, cutters for simultaneously operating on two of the blanks, means coacting with the templates for varying the positions of the blanks relatively to the cutters, and means independent of the templates for raising the carriers and the parts carried thereby as they move from one cutter to the other.

3. A machine of the character described, comprising an intermittently rotatable turret having a plurality of vertically movable slides, a spindle mounted in each slide, a pair of templates and a blank clamp carried by each spindle, a shaft having a pair of cutters, means adjacent each cutter for coacting with one of the templates to vary the height of the slide, and means for simultaneously rotating two of the spindles while the blanks carried thereby are in proximity to the cutters, said means comprising automatic clutch-controlled mechanism for imparting rotary motion to the spindle.

4. A machine of the character described, comprising a continuously rotatable shaft having a cutter at each end and a roll adjacent to each cutter, an intermittently rotatable turret having four equi-distant vertically movable slides, each having a roll, cam tracks over which said rolls ride, a spindle mounted in each slide, a pair of templates, and a blank clamp carried by each spindle, said templates being positioned to enable but one of them to coat

with the roll adjacent to each cutter, and means for rotating the spindles while they are in positions to present two blanks to the cutters.

5. A machine of the character described, comprising a rotatable turret, a work-clamp carried by said turret and mounted to rotate in a plane substantially at a right angle to the plane of rotation of the turret, a plurality of rotary cutters having their axes parallel to said plane of rotation of the turret, and pattern-controlled mechanism for varying the distance between the axis of the clamp and the axis of the cutter operating on the work held by said clamp.

6. A machine of the character described, comprising a rotatable turret, a work-clamp carried by said turret and mounted to rotate in a plane substantially at a right angle to the plane of rotation of the turret, a rotary shaft parallel with said plane of rotation of the turret, and having a cutter at each end, and pattern-controlled mechanism for varying the distance between the axes of the clamp and shaft.

7. A machine of the character described, comprising a shaft having a pair of cutters, a carrier movable in a plane parallel with said shaft and having a blank-clamp rotatable in a plane at a right angle to the plane of movement of said carrier, and independent template or pattern devices to

control the actions of the cutters on a blank mounted in said clamp.

8. A machine of the character described, having a shaft carrying two cutters, a carrier intermittently rotatable in a plane parallel with said shaft, and having a blank-clamp rotatable plane at a right angle to the plane of rotation of the said carrier, and independent template or pattern devices to control the actions of the cutters on a blank mounted in said clamp.

9. A machine of the character described, having a shaft carrying two cutters, a turret intermittently rotatable in a plane parallel with said shaft and having a plurality of blank-clamps rotatable in planes at a right angle to the plane of rotation of said turret, and a pair of differently shaped patterns adjacent to each blank-clamp to control the actions of the cutter on each blank mounted in a clamp.

10. A machine of the character described, comprising a shaft carrying two cutters, a plurality of blank clamps intermittently movable in a plane parallel with said shaft, and also rotatable in planes at a right angle thereto, a pair of templates rotatable with each clamp, and supports adjacent to the cutters for said templates.

In testimony whereof I have affixed my signature.

GUY B. BROWN.
